COMBINED ELECTRICALLY VIBRATED MASSAGER AND SUPPORT

Edwin M. Vogt, Kalamazoo, Mich.

Application December 27, 1948, Serial No. 150,365

Term of patent 14 years

(Cl. D83—1)

To all whom it may concern:

Be it known that I, Edwin M. Vogt, a citizen of the United States, residing at Kalamazoo, in the county of Kalamazoo and State of Michigan, have invented a new, original, and ornamental Design for a Combined Electrically Vibrated Massager and Support, of which the following is a specification, reference being had to the accompanying drawing, forming part thereof, in which:

Fig. 1 is a front perspective view, and

Fig. 2 is a side elevational view of combined electrically vibrated massager and support showing my new design.

The rear end of the body and the side of the body not shown are substantially the same as the front end and side illustrated.

I claim:

The ornamental design for a combined electrically vibrated massager and support, as shown and described.

EDWIN M. VOGT.
